BROACH

Roland T. Bess and Archie I. Bess, Salt Lake
City, Utah

Application June 26, 1948, Serial No. 35,436

5 Claims. (Cl. 29—95.1)

1

The present invention relates to an improved means for cutting or slotting sheet materials, and more particularly for cutting tapered notches in the edges of preferably a plurality of sheet like articles, such as cards, sheets of paper, cardboard, fiber, and the like. The invention relates especially to a cutting device of the broaching type for slotting or notching index cards, for filing purposes, and the like, but it has other applications and it will be understood that other uses are contemplated.

The use of notched cards for mechanical filing, sorting, tabulating, indexing, and the like, has expanded rapidly in recent years, and the provision of the indexing or control notches and slots, has become an important limiting factor in systems of this character. In one system which has come into wide general use, the required notches have conventionally been prepared by hand punches, operating on single cards, with consequent inefficiency and expense which have made such card systems unsuitable for many types of operations. Considerable difficulty has been encountered in obtaining clean and accurate slots or notches in sheets of paper, cards, and the like, and particularly in the slotting or notching of record and index cards such as are used in filing systems, and the like, where in the character and/or location of the notches or slots determines classification, filing, etc., of the article. It is not particularly difficult to cut single cards but it has been found very difficult to secure a smooth clean cut when a plurality of cards are cut at one time.

It is an object of the present invention to cut, slot, or notch cards and other articles of sheet material efficiently, rapidly, and economically, and particularly to notch a plurality of such articles simultaneously.

It is another object of the present invention to secure clean, smooth cuts in cards of paper and other fibrous stock, and analogous articles, by designing an efficient cutting or slotting apparatus which is sufficiently sturdy for heavy duty and for cutting or slotting (or notching) a stack of cards at a single operation, and at the same time is suitable for making a clean smooth cut.

Still another object is to design a cutting apparatus which is efficient in operation and may be operated with a minimum of power and which, at the same time, is self-cleaning and not subject to stoppage and damage to stock by reason of accumulations of fiber, lint, and the like, as

2

commonly occurs in apparatus for paper cutting, punching, notching, and the like.

Other and further objects are to provide an efficient cutting or punching apparatus, by proper provision of rake, clearance, and cutting angle of the cutting or punching elements, and also by the arrangement of successively deeper and narrower cutting elements in series, with special provision of waste openings for the removal of accumulations of lint and the like between successive of said elements in said series.

Additional objects will become apparent as this description proceeds and accordingly reference will next be made to the accompanying drawings wherein:

Fig. 1 is a vertical side elevational view showing the principal cutting die of the present invention, cooperating die element being shown in section;

Fig. 2 is an isometric view of the cutting dies of Fig. 1, showing dies in operative relationship;

Fig. 3 is an edge view in elevation of the principal or male die of Figs. 1 and 2;

Fig. 4 is a plan view of the die assembly of Fig. 2;

Fig. 5 is a horizontal sectional view taken substantially on the line 5—5 of Fig. 1, showing a shallow and broad cutting or slotting element of the male die;

Fig. 6 is a horizontal section view taken substantially along the line 6—6 of Fig. 1, showing a narrow deep cutting or slotting element;

Fig. 7 is a fragmentary elevation of one half of the male die assembly, showing in somewhat exaggerated extent the angle of inclination of the cutting elements and their relationship to the clearance slots for waste;

Fig. 8 is a fragmentary and somewhat diagrammatic view showing the arrangement of the male and female cutting dies with respect to a stack of sheets in a card slotting operation; and

Fig. 9 is a fragmentary plan view of a notched card element, typical of the work performed by the apparatus and method of the present invention.

Referring first to Figs. 1 and 2, there is shown a slotting or notching die assembly consisting of the principal or male die element indicated generally at 11 and the cooperating female die element indicated generally at 13. As herein shown the female die is a single piece of suitable die material, such as hardened steel, which is adapted to be firmly mounted in an appropriate recess, such as that shown at 15, Fig. 8, in a solid frame or table member 17, shown only

fragmentarily in Fig. 8. The female die member 13 may be suitably secured to the table member as by bolts or studs 19, or the like. In general, the principal male die is the movable element but the die may be held stationary and the material to be cut moved relatively thereto if desired. The female die 13 is provided with elongated openings 19A to permit accurate adjustment and alignment.

The principal or male die 11, as herein shown, is preferably made in two halves 21, 23, identical in every respect except that they are conjugate, that is one is of right hand configuration and the other is of left hand configuration. If desired, this die may be made in a single piece, but for its economical manufacture it is simpler to make it in two parts. The two parts are firmly secured together by suitable means, such as screws 25, or rivets may be employed if desired. For nearly all practical purposes, the male die remains assembled as a unit, except when it might be desirable or necessary to take the two halves apart for repair or cleaning.

Referring again to Fig. 4 (see also Fig. 9) it will be noted that at its greatest depth the cutting element and the notch to be formed are of tapered form, resembling a blunt wedge. Obviously, other shapes might be used. The male die is formed with a series of cutting edges which in the present instance, as shown in Figs. 1 and 3, are progressively narrower and deeper until the last cutter, as seen near the top of these figures, projects to the full final depth of the notch to be formed. Cutters of this general form are known for cutting teeth in metal gears and the like, but the novelty of the present invention resides in the particular arrangement of the cutters, secondary cutters, and provision made for removing waste lint and fiber, as will be described hereinafter.

The first or lowermost cutting element 31 as seen in Figs. 1, 2 and 3, is a shallow cutter (having a depth for example, of the order of about $\frac{1}{16}$ inch) with a cutting edge substantially of the width of the base of the slot to be cut (Fig. 9). The front or forward edge (to the right in Fig. 1) may be at right angles to the axis of the tool 11, i. e. the edge may be horizontal, but it is preferably arranged at a slight angle for easier cutting. The cutting element 33 corresponds in section to the first cutter 31, but projects further, to approximately twice the depth of cutter 31. The next cutting elements, shown at 35, 37, are similar to element 33 but project still deeper, as is common with broaching tools. The fifth cutter 39 projects far enough that its side edges have substantial dimensions and therefore, in the present embodiment, this cutting element is provided with a secondary cleaning cutter for trimming fiber which was not cut cleanly in the passage of the forward edges of cutting element 39. The secondary cutter, which is an important feature of this invention, as indicated in Figs. 1, 3 and 8, and is formed by cutting a V-shaped groove 39A of an apex angle of about 45 to 90°, preferably about 60°, in such a manner as to present a square or slightly acute cutting or trimming edge 39B (Fig. 8).

In cutting fibrous material such as cardboard or paper, there is always a tendency to tear slightly, leaving projecting fibers behind the cutting edge of each element 31, 33, 35, 37 and so on. Thus, even though the edge such as 31 is quite sharp, there will usually be some slightly torn

fiber which is not cut perfectly clean. The secondary cutting edge 39B trims these projecting uncut fibers away before the approach of the next succeeding cutting element 41 which extends deeper into the stock being processed but it does not extend farther laterally than the element 39. The first two or three cutters, such as 31 and 33, ordinarily do not project far enough to have side cutting edges of sufficient depth to require the secondary cutters, but it will be obvious that such might be provided if desired.

The next succeeding cutter 41 is similarly provided with a secondary side trimming or cleaning cutter 41B, formed by providing a V-notch or groove 41A similar to groove 39A in the side of element 41. The notches such as 39A and 41A are preferably formed about the middle of the side face of each of the tooth-like cutting elements 39, 41, etc. These auxiliary or secondary cutting elements may also be provided, if desired, across the forward face of the tooth or cutting element 31, but they are not particularly essential across the forward face because each successive cutter projects farther into the stock and trims away any uncut fiber that might be left by the preceding element. It is understood of course that the side edges of all of the cutters are in vertical alignment, or in a common vertical plane, or substantially so.

30 The succeeding cutting teeth or elements 43, 45, etc. extend progressively deeper and are provided with the secondary grooves 43A, 45A, etc., to provide corresponding cutting edges 43B, 45B, etc. As shown in Fig. 1, the advance edges (lower surfaces as seen in this figure) of successive cutting elements are disposed substantially at right angles to the travel of the tool, a slight rake angle being provided. In Fig. 7, the rake angle is shown somewhat exaggerated to make this feature clear. The grooves 39A, 41A, 43A, and so on, are parallel or substantially parallel to the advance side cutting elements of the cutters 39, 41, 43, etc., as shown in Fig. 1.

45 While the secondary or cleaning cutters 39B, 41B, 43B, and so on, are ordinarily preferred and are frequently essential, they may be dispensed with for certain types of other stock to be cut. They are therefore a desirable but not always an essential feature of the invention.

Immediately in advance of each cutting element such as 31, 33, 35, 37, 39, etc., there is provided a waste ejection opening which extends more or less horizontally from front to rear through the body of the tool to provide a passageway for the ejection of fibers, dust, lint, and the like, so as to keep the cutting edges clean. Thus, in front of the first cutter 31, an opening 61 is formed, preferably with a width equal or substantially equal to that of the forward edge of that particular element. In advance of the second element 33 is a similar opening 63, of a width about equal to that of cutter 33, and likewise an opening 65 is in advance of cutting element 35, an opening 67 in front of cutter 37, opening 69 in front of cutter 39, and so on. Some of the cutting elements are not shown with reference characters. The last cutting element 51, 70 Figs. 1 and 3, is provided with an opening 81 immediately in advance thereof and since this cutter is narrowest of all, at its advance edge, in the embodiment of the invention shown in the drawings, the opening 81 is the narrowest of all the openings, as is evident in Figs. 2, 3, and 6. Be-

cause the die 11 is deepest (thickest from front to rear) at the last cutting element, the opening 81 extends for a greater distance than any of the others. Preferably, and as shown in Fig. 1, a clearance space is provided in advance of the forward portion of each cutter element, and these clearance spaces, indicated respectively at 62, 64, 66, etc., beginning at the bottom, up to and including the upper space 82 are aligned with and about equal in vertical extent with the openings 61, 63, 65, etc., up to 81 with which they directly connect. In the construction shown, all the clearance spaces 62, 64, etc., are of substantially equal depth rearwardly from the adjacent cutting edge. This depth may be varied considerably but as shown it is of the order of about two, or three, or four times the distance which each cutting element extends beyond the previous cutting element in the series. One purpose of these clearance spaces is to provide a receptacle for cut particles and also to provide accumulating pockets for dust, lint, and other waste, as will be more fully explained.

In Figs. 5 and 6 there are shown sectional views which illustrate clearly the variations in cutting depth and dimension of the clearance openings. In Fig. 5 one of the first waste ejection openings such as 63 is shown, the section being taken between the first and second cutter elements 31 and 33. It will be noted, as mentioned above, that the opening 63 is about as wide as the base 91 of the notch, Fig. 9, corresponding to the width of the forward cutting edge of the second cutting element 33. By contrast, the opening 81 adjacent the last cutter 51 (Fig. 1) is shown in Fig. 6 as being long but relatively narrow, the width being approximately equal to that of the apex 92 of the notch, Fig. 9. Intermediate openings of course are of intermediate width and length, becoming longer and narrower from bottom to top, as seen in Figs. 1, 2 and 3.

In Fig. 7 there is shown a fragment of one half of the two part male die of Figs. 1 to 3, illustrating how the openings such as 81 may be formed by machining transverse grooves in each half before assembling. As previously indicated, the angle of rake indicated in this figure is shown somewhat exaggerated beyond that which would normally be used, although this angle may be varied considerably.

By machining the two halves of the die 11 before assembly, so that the cutter elements and the grooves which form waste ejection openings may match accurately, the die may be produced economically. The openings 61, 63, etc., could of course be drilled and broached out, or formed in any other suitable manner, in case it is preferred to make the male die 11 of a single piece of material, but this is not usually considered necessary.

It will be understood that air or other fluid may be forced through the openings 61, 63, etc., in either direction, to draw the waste, lint, etc., through the openings, or to blow it away from the die, as will be apparent to those skilled in the art.

Fig. 8 shows how the male die 11 may be used for notching a stack of cards or the like. The cards C may be positioned upon a suitable support such as table member 17, by any suitable positioning means (not shown) so that they are in vertical alignment on all sides and in such position that the portion to be punched or slotted lies directly over the opening 13A of the complementary die 13 (Fig. 4). With the cards held firmly in this position, the broaching tool 11 de-

scends (being mounted on and operated by a suitable plunger or the like, not shown). Each successive cutting element 31, 33, 35, etc., slices a thin cutting out of each card, and the secondary cutter edges 39B, 41B, 43B, etc., shave off cleanly any fibers at the edges of the slot as the slot in each card becomes progressively deeper.

As the broaching die 11 descends some small fibers may not be carried down with it and may tend to slide upwardly, relatively to the vertical face of each cutting element. This is particularly true after the cutting edges become slightly dull. The recesses or pockets 62, 64, 66, etc., in front of each advancing cutting element provide spaces into which the cut waste as well as lint or fiber waste may accumulate. Air evacuating means (not shown) may be connected to a suitable connection, such as a perforated block (not shown) in sliding contact with the rear edge of die 11, so as to apply suction to each of the waste openings 61, 63, 65, and so on up to opening 81. Obviously, this will remove the waste and other fiber, etc., from the pockets 62, 64, etc., and prevent clogging. Alternatively, if desired, compressed air or other fluid may be applied to the openings, as by means of a perforated block or connection such as suggested above. Such block should be adjusted to provide a smooth relatively air tight fit against the back edge of the die 11. If compressed air rather than suction is used, it should be applied at a point in the vertical movement of the die 11 where the waste, including dust and lint, can be ejected forwardly (to the right as viewed in Fig. 1) either well above the cards or like, C, or below the table member 17. A suitable receptacle (not shown) may be provided for receiving the waste fiber. Ordinarily the amount of waste removed on each stroke is very small, and most of it would drop out of the die, but it is preferable to remove it during each cycle, either on the cutting stroke or the return, or both. However, if desired, means may be provided for cleaning the die only periodically, as will be evident to those skilled in the art.

From the foregoing description it will be apparent that the invention may be modified in various respects. In the embodiment shown in Figs. 1, 2 and 3, the male die 11 has some 22 cutting elements. This number has been found quite satisfactory in practice but it is obvious that it may be varied widely. As indicated above, it is usually not necessary to provide all of the successive cutting elements such as 31, 33, 35, 37, 39, etc., with the secondary side grooves and cleaning cutter elements 39B, 41B, 43B, and so on. These may be omitted altogether for certain types of work but it is ordinarily desirable to have at least some of them, particularly on the sides of the intermediate cutters, to clean the uncut fibers from the sides of the slots. This enables the die 11 to operate smoothly and with less power than would be required otherwise. The slight inclination of all cutting elements from a horizontal plane is also advantageous because it saves power.

While the above description has been based on a particular device for forming a particular kind of tapered notches in cards, it is apparent that the particular shape of the notch or a particular type of material to be punched are not limiting features of the invention. Various notches and slots may be formed in various materials, and the device may be used for cutting off stock, cutting off corners, and for various analogous purposes as will be understood by those skilled in

the art. Other arrangements, modifications, and adaptations will suggest themselves to those skilled in the art and it is intended that those which fall within the spirit of this invention shall form a part of this invention. Hence the invention and its use are not limited otherwise than as required by the scope of the appended claims.

What is claimed is:

1. A broaching device for notching paper cards and the like, comprising a unitary body structure equipped with a series of slots, each slot being slightly narrower than its predecessor, each slot being adjacent a broaching cutter of progressively greater depth and progressively narrower forward cutting edge, each of said slots serving as a waste ejecting opening adjacent each cutter, the width of each of said openings corresponding approximately to the width of the respective forward cutting edge.

2. A broaching device for cutting paper stock and the like, comprising a pair of body members assembled into a unitary body and a series of tapered cutters of progressively deeper and narrower arrangement formed unitary with said body, said cutters being designed to broach a tapered notch into a stack of material to be cut, the lateral cutting edges of successive cutters being arranged in common converging planes, successive lateral cutting edges being separated by grooves cut into said planes to provide secondary cutting elements, the progressively deeper cutting edges being progressively narrower across their forward edges, and a waste ejection opening adjacent each cutter, extending from the forward cutting edge rearwardly through the body of said device and of transverse width substantially equal to the width of the adjacent forward cutting edge.

3. A broaching cutter for forming tapered notches in material, comprising two opposed body members secured together as a unitary body structure, each of said members being provided with a series of matched cutters of progressively deeper and narrower configuration at forward cutting edges, and a groove adjacent each cutting element so arranged that when the said members are assembled the corresponding grooves in said members join to form a waste ejection passage through said structure, adjacent each cutter and in position to remove waste cut there-

by, said passages being progressively narrower transversely correspondingly to said series of cutters.

4. A broaching device of the character described, comprising a cutter arranged for relative movement with respect to material to be broached, said cutter being provided with a series of blades each disposed transversely to the direction of said relative movement, successive blades of said series being progressively narrower and deeper so as to form progressively a tapered slot, a waste discharge opening between each successive pair of said blades said openings each being of a width substantially equal to that of the blade following, the forward cutting edge of each blade element having a cutting angle of slightly less than 90° to provide an advance rake, each of said elements having also lateral cutting elements with a cutting angle of less than 90°, and secondary lateral trimming cutting edges between successive blade elements.

5. In a device of the character described for punching fibrous material, a two part body of symmetrical members secured rigidly to form a unitary structure, a series of broaching cutters of progressively narrower and deeper section, a waste pocket in advance of each cutter, a waste ejection of width greater than the preceding cutter and substantially equal to the immediately following cutter opening connected to each pocket, and a V-groove in the side of at least a plurality of said cutters arranged so as to provide an acute angled cleaning cutting edge for removing fiber left by said cutters.
